UNITED STATES PATENT OFFICE.

FLORENCE F. CONNER, OF CINCINNATI, OHIO.

DESIGN FOR A HARNESS GAG-RUNNER.

SPECIFICATION forming part of Design No. 28,235, dated February 1, 1898.

Application filed March 29, 1897. Serial No. 629,866. Term of patent 14 years.

To all whom it may concern:

Be it known that I, FLORENCE F. CONNER, of Cincinnati, in the county of Hamilton and State of Ohio, have invented a new and original Design for Harness Gag-Runners, of which the following is a full, clear, and exact description, reference being had to the accompanying drawings, forming part of this specification, in which—

Figure 1 is a plan view of a gag-runner embodying my design, and Fig. 2 is a vertical section on the line II II of Fig. 1.

The design consists in a gag-runner having the form and contour herein described and claimed.

In the drawings, 2 represents a frame having end bars 3 3, side bars 4 4, a cross-bar 5, and a middle stud 6. The side bars at the middle drop inwardly below the plane of the end bars, as shown in Fig. 2. At one end of the frame 2 is a loop 8.

I claim—

The design for gag-runners substantially as herein described and shown.

In testimony whereof I have hereunto set my hand.

FLORENCE F. CONNER.
